[57] CLAIM

The ornamental design for a computer console, as shown and described.

DESCRIPTION

FIG. 1 is a perspective view showing the top, front, and left side of the computer console showing our new design;

FIG. 2 is a top plan view of the computer console;

FIG. 3 is a front elevational view of the computer console on an enlarged scale;

FIG. 4 is a rear elevational view of the computer on an enlarged scale;

FIG. 5 is a left elevational view of the computer console on an enlarged scale;

FIG. 6 is a right elevational view of the computer console on an enlarged scale; and

FIG. 7 is a bottom plan view of the computer console shown on a reduced scale relative to FIGS. 1 through 6.
